Primary Examiner — S. Bryan Reinholdt, Jr.*Assistant Examiner* — Kaitlan Walker(74) *Attorney, Agent, or Firm* — Luedeka Neely, P.C.(57) **CLAIM**

The ornamental design for an archery sight as shown and described.

DESCRIPTION

FIG. 1 is a perspective view of an archery sight of my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof; and,

FIG. 8 is a perspective view depicting the archery sight mounted onto an archery bow.

The broken lines in all the figures depict portions of the archery sight that form no part of the claimed design. The broken lines in FIG. 8 depict environment of an archery bow that form no part of the claimed design.
